UNITED STATES PATENT OFFICE.

BERNARD LASTER, OF PHILADELPHIA, PENNSYLVANIA.

WOMAN'S UNDERGARMENT.

Application filed August 21, 1925. Serial No. 51,595.

To all whom it may concern:

Be it known that I, BERNARD LASTER, a citizen of the United States, residing in Philadelphia, Pennsylvania, have invented 5 a Woman's Undergarment, of which the following is a specification:

This invention relates to women's undergarments of the bifurcated type. One object of the invention is to provide a garment 10 of this type which can be easily and conveniently opened at either side. A further object is to provide an improved form and arrangement of parts whereby increased comfort is obtained for the wearer, while 15 at the same time simplifying manufacture. Still other objects will be apparent from the following specifications and claims.

In the accompanying drawing I have shown the embodiment of the invention 20 which I now deem preferable but it will be understood that the drawing is for illustrative purposes only and that various changes and substitutions may be made within the scope of the appended claims without de- 25 parting from the spirit of the invention.

Of the drawing,

Fig. 1 is a rear view of a garment embodying the invention.

Fig. 2 is a side view.

Fig. 3 is a detached perspective view 30 showing one of the pieces of material from which the garment is made.

Referring to the drawing, it will be seen 35 that the garment is entirely symmetrical throughout, consisting of right and left combined body and leg sections. Each of these sections includes a single piece of fabric 1 or 1^a which extends down the front, through the crotch and up the rear. These two 40 pieces are centrally joined at a single continuous seam 2. The lower or intermediate parts of these pieces 1 and 1^a extend laterally and downward and are sufficiently wide at the bottom to form the leg portions of 45 the garment.

Each of the pieces 1 and 1^a is wider at its upper front end than at its upper rear end, and the upper portions of the two outer edges of the respective pieces are connected 50 together by panels 3 and 3^a, seams being formed at 4 and 5. The upper edges of all of the several pieces are connected with a waist band at 6, this band preferably being elastic. This elastic waist band in conjunction 55 with other features to be described make it possible for the garment to be worn

either underneath or over a corset, as desired.

The panels 3 and 3^a are preferably shorter than the corresponding parts of the leg 60 pieces 1 and 1^a, and preferably each front seam 4 extends downward throughout substantially the entire length of the panel. On account of the greater widths of the front portions of the pieces 1 and 1^a the 65 seams 4 are at the side of the leg portions and the seams 5 are at the rear thereof. These rear seams 5, however, are quite short, thus providing in each leg portion an opening or slit 6^a which extends from the bottom 70 to a point near the waist line or at least to the line of the hips of the wearer. The panels are made full and their rear lower parts form flaps 7 which normally extend 75 rearward and inward to cover the before-mentioned slits 6^a. Preferably these flaps are not fastened except as aforesaid.

I provide means whereby the edges of the slits may be releasably connected at the bottoms thereof, this means comprising suitable hooks and eyelets or clasps, as indicated at 8. Preferably a band or elastic extends around the bottom of each leg portion, as shown at 9, and this band may be formed or woven in place on the fabric according to 80 a method well known in the art. The elastic may come either above or below the knee of the wearer, as initially determined by the designer of the garment.

Preferably each panel 3 and 3^a is gathered and is provided with a horizontal strip of elastic 10, which may be formed or woven in place. These elastics 10, 10 serve to provide a snug fit about the hips without interfering with freedom of movement. 90

It will be understood from the foregoing description, that the garment may be opened at either side, as desired to suit the convenience of the wearer, by unfastening one or the other of the clasps 8 and drawing the 100 corresponding flap 7 to one side.

The cut of the garment in such as to allow entire freedom of movement, and at the same time avoid any excess material between the legs. It is particularly to be noted 105 that there are no seams running vertically along the inner sides of the leg sections.

What I claim is:

1. In a woman's bifurcated undergarment, the combination of two combined body and leg sections joined by a central seam, each of the said sections having a slit in the rear 110

- extending from the bottom to a point near the waist, releasable means for connecting the two edges of each of the slits at the bottoms thereof, and flaps attached respectively 5 at the outer sides of the said slits and overlapping the rear parts of the respective leg portions.
2. In a woman's bifurcated undergarment, the combination of two combined body and leg sections joined by a central seam, each 10 of the said sections having a slit in the rear extending from the bottom to a point near the waist, elastics located at the bottoms of the respective leg portions and divided at 15 the said slits, releasable means for connecting the ends of the said elastics, and flaps attached respectively at the outer sides of the said openings and overlapping the rear parts of the respective leg portions.
3. The combination in a woman's bifurcated undergarment, of two combined body and leg sections each including a single continuous piece of fabric extending down the front, through the crotch and up the 20 back, the intermediate parts of the said pieces being extended downward to form leg portions and the upper front parts of the pieces being wider than the upper rear parts, a single continuous central seam joining the inner edges of the said pieces, panels respectively connecting the upper portions of the two outer edges of each of the said pieces, the said panels being respectively seamed throughout substantially their entire lengths to the front parts of the said continuous pieces and overlapping the lower rear parts 25 of the said pieces and being free from direct attachment thereto, and releasable means for connecting the edges of the said leg portions at the extreme bottoms thereof.
4. The combination in a woman's bifurcated undergarment, of two combined body 30 and leg sections each including a single continuous piece of fabric extending down the front, through the crotch and up the back, the intermediate parts of the said pieces being extended downward to form leg portions and the upper front parts of the pieces being wider than the upper rear parts, a single continuous central seam joining the inner edges of the said pieces, panels respectively connecting the upper portions of the two outer edges of each of the said pieces, the said panels respectively overlapping the lower rear parts of said continuous pieces 35 and being free from direct attachment thereto, elastics extending across the said panels at the hip line, and releasable means for connecting the edges of the said leg portions at the extreme bottoms thereof.

and leg sections each including a single continuous piece of fabric extending down the front, through the crotch and up the back, the intermediate parts of the said pieces being extended downward to form leg portions 45 and the upper front parts of the pieces being wider than the upper rear parts, a single continuous central seam joining the inner edges of the said pieces, panels respectively connecting the upper portions of the two outer edges of each of the said pieces, the said panels being respectively seamed throughout substantially their entire lengths to the front parts of the said continuous pieces and overlapping the lower rear parts 50 of the said pieces and being free from direct attachment thereto, and releasable means for connecting the edges of the said leg portions at the extreme bottoms thereof.

5. The combination in a woman's bifurcated undergarment, of two combined body and leg sections each including a single continuous piece of fabric extending down the front, through the crotch and up the back, the intermediate parts of the said pieces 55 being extended downward to form leg portions and the upper front parts of the pieces being wider than the upper rear parts, a single continuous central seam joining the inner edges of the said pieces, panels respectively connecting the upper portions of the two outer edges of each of the said pieces, the said panels respectively overlapping the lower rear parts of said continuous pieces 60 and being free from direct attachment thereto, elastics extending across the said panels at the hip line, and releasable means for connecting the edges of the said leg portions at the extreme bottoms thereof.

BERNARD LASTER.
